CLAIM

I claim the ornamental design of a bilge pump, as shown and described herein.

DESCRIPTION

FIG. 1 is a perspective view of a bilge pump showing the present invention;

FIG. 2 is a front view of the bilge pump in FIG. 1 showing the present invention;

FIG. 3 is a back view of the bilge pump in FIG. 1 showing the present invention;

FIG. 4 is a side view of the bilge pump in FIG. 1 showing one side of the present invention;

FIG. 5 is a side view of the bilge pump in FIG. 1 showing the other side of the present invention;

FIG. 6 is a top view of the bilge pump in FIG. 1 showing the present invention; and,

FIG. 7 is a bottom view of the bilge pump in FIG. 1 showing the present invention.

The broken line showing of the bilge pump in FIGS. 1-4 and 6-7 is for the purpose of illustrating environmental structure and forms no part of the claimed design.
